Primary Examiner — Kelley A Donnelly(74) *Attorney, Agent, or Firm* — Leanne Taveggia Farrell; Westman, Champlin & Koehler, P.A.(57) **CLAIM**

The ornamental design for a display shelf, as shown and described.

DESCRIPTION

FIG. 1 is a perspective view of a display shelf showing our new design;

FIG. 2 is a side view thereof, the opposing side, the front and the back being identical; and,

FIG. 3 is a top view thereof.

The broken lines shown in the drawings are included for purposes of illustrating portions of the display shelf and form no part of the claimed design.

1 Claim, 2 Drawing Sheets(56)
